United States Patent Office

Des. 177,299
Patented Mar. 27, 1956

177,299

DESK

Russel Wright, New York, N. Y., assignor to Shwayder
Brothers, Ecrose, Mich., a corporation of Colorado

Application February 24, 1955, Serial No. 34,664

Term of patent 14 years

(Cl. D33—7)

Fig. 1 is a perspective view of a desk showing my new design; and

Fig. 2 is a rear elevational view thereof upon a reduced scale.

I claim:

The ornamental design for a desk, substantially as shown.
